[57] CLAIM

The ornamental design for a covered sled for transporting a person in lying position, as shown and described.

DESCRIPTION

FIG. 1 is a perspective view of a covered sled for transporting a person in lying position showing my new design;

FIG. 2 is a top plan view of the design;

FIG. 3 is a side elevational view of the design showing the other side from that shown in FIG. 1;

FIG. 4 is a bottom plan view of the design;

FIG. 5 is a front elevational view of the design; and,

FIG. 6 is a rear elevational view of the design.

FIG. 1

FIG. 6
